UNITED STATES PATENT OFFICE.

NATHAN LIDZBARSKY, OF NEW YORK, N. Y.

DESIGN FOR A WEDDING RING.

Application filed March 20, 1925. Serial No. 12,782. Term of patent 3½ years.

To all whom it may concern:

Be it known that I, NATHAN LIDZBARSKY, a citizen of the United States, residing at New York, in the county of New York and State of New York, have invented a new, original, and ornamental Design for a Wedding Ring, of which the following is a specification, reference being had to the accompanying drawing, forming part thereof.

Fig. 1 is a perspective of a wedding ring, showing my design.

Fig. 2 is a side view of said wedding ring.

Fig. 3 is an edge view of the same. The specific illustration in Figs. 1 and 2 extends throughout the size of the ring.

I claim:

The ornamental design for a wedding ring, as shown.

In testimony whereof I have affixed my signature.

NATHAN LIDZBARSKY.
